US00D721286S

(12) **United States Design Patent**
Saguchi

(10) **Patent No.:** **US D721,286 S**
(45) **Date of Patent:** ** *Jan. 20, 2015

(54) **CONTROLLED-RELEASE CHEMICAL
DELIVERY DEVICE**

(75) Inventor: **Ryuichi Saguchi**, Joetsu (JP)

(73) Assignee: **Shin-Etsu Chemical Co., Ltd.**, Tokyo (JP)

(*) Notice: This patent is subject to a terminal disclaimer.

(**) Term: **14 Years**

(21) Appl. No.: **29/380,789**

(22) Filed: **Dec. 10, 2010**

(30) **Foreign Application Priority Data**

(57) **CLAIM**

I claim the ornamental design for a controlled-release chemical delivery device, as shown and described.

DESCRIPTION

FIG. 1 is a front elevation view of a controlled-release chemical delivery device showing my new design;

FIG. 2 is a rear elevation view thereof;

FIG. 3 is a top plan view thereof;

FIG. 4 is a bottom plan view thereof;

FIG. 5 is a right side elevation view thereof;

FIG. 6 is a left side elevation view thereof;

FIG. 7 is a perspective view thereof;

FIG. 8 is an enlarged partial view thereof taken along line 8-8 in FIG. 1; and,

FIG. 9 is a cross-section view thereof taken along line 9-9 in FIG. 8.

1 Claim, 7 Drawing Sheets
